(57) **CLAIM**

The ornamental design for a radio frequency identification tag reader, as shown and described.

DESCRIPTION

FIG. 1 is a front perspective view of a radio frequency identification tag reader;

FIG. 2 is a rear perspective view thereof;

FIG. 3 is a top view thereof;

FIG. 4 is a front view thereof;

FIG. 5 is a right-side view thereof, the left-side view being a mirror image;

FIG. 6 is a rear view thereof; and,

FIG. 7 is a bottom view thereof.

The broken lines depict environmental subject matter only and form no part of the claimed design.

1 Claim, 4 Drawing Sheets

FIG. 3

FIG. 4

FIG. 5

FIG. 6

FIG. 7
